R. E. CARMICHAEL.
SULFUR MINING APPARATUS.
APPLICATION FILED MAY 27, 1918.

1,287,879.

Patented Dec. 17, 1918.

UNITED STATES PATENT OFFICE.

ROBERT E. CARMICHAEL, OF DAMON, TEXAS, ASSIGNOR OF ONE-HALF TO GEORGE HAMMAN, OF HOUSTON, TEXAS.

SULFUR-MINING APPARATUS.

1,287,879.

Specification of Letters Patent. Patented Dec. 17, 1918.

Application filed May 27, 1918. Serial No. 236,706.

To all whom it may concern:

Be it known that I, ROBERT E. CARMICHAEL, a citizen of the United States, residing at Damon, Brazoria county, Texas, have 5 invented a certain new and useful Improvement in Sulfur-Mining Apparatus, of which the following is a full, clear, and exact description, such as will enable others skilled in the art to which it appertains to make 10 and use the same.

My invention relates to apparatus for sulfur mining and has particular application to apparatus used in mining by means of thermal solvents. In this system of mining, a 15 sulfur mine or well is drilled down through the bed of subterranean sulfur or other material to be mined and into this well my improved system of pipes is placed.

Hot water, steam or other thermal solvent 20 is introduced forcibly into contact with the sulfur which is fused by the heat of the solvent and runs down in molten condition to the bottom of the well. The pressure of the heated fluid forced down the outer pipes 25 serves to raise the sulfur in the central sulfur return pipe toward the surface of the ground. The upward course of the current of sulfur is assisted by means of an upward current of air or steam which is forced 30 down another pipe and discharged near the lower end of the sulfur pipe and bubbles up through the rising current of sulfur.

The main object of my invention is to provide an improved means of introducing air 35 or steam into the lower end of the liquid outlet pipe in sulfur, oil or other wells for the purpose of assisting in lifting these liquids to the surface.

Another object is to so introduce the air or 40 steam into a liquid outlet pipe as to assist in lifting the liquid to the surface without having the air or steam inlet pipe in such position as to impede the upward progress of the fluid.

Another object is to so arrange the air or 45 steam inlet as to produce no appreciable back pressure at its point of discharge into the liquid outlet pipe.

Other advantages in simplicity and durability of construction will more clearly appear in the detailed description which follows.

Referring now to the drawing forming a 50 part of this specification, Figure 1 is a longitudinal section of the concentric system of pipes constituting my invention showing

the part of my apparatus which is inserted into the well. Fig. 2 is a side view of the upper portion of the system of pipes shown in Fig. 1 showing that part above ground, 60 which includes the inlets and outlets for the liquids.

In the drawing, like numerals are applied to like parts throughout the views. The wall of the well is reinforced by the casing 65 1 near the upper part thereof. This casing is extended downwardly ordinarily to seat upon the rock strata.

The outer pipe, 2, of my system of pipes is extended down into the well and is anchored at its lower end by being threaded, 70 as at 5, to the compound coupling 4, said coupling being threaded at the base thereof for attachment to the anchoring pipe 6. The anchoring pipe is rigidly held within 75 the lower end of the well, which is extended downwardly 50 or 75 feet beyond the sulfur strata for this purpose. The lower part of the pipe 2 for the full depth of the sulfur stratum is perforated at 3 to furnish an 80 outlet for the heating fluid. The upper end of the pipe 2 projects above the ground for a short distance and terminates in a T joint 7, having at its upper end a stuffing box 11 whereby it fits fluid tight around the next 85 inner concentric pipe 12. A lateral inlet pipe 8 is connected to the T 7, on one side, while on the other, I connect a relief pipe 9 provided with a relief valve 10 to provide 90 against excess pressure exerted by the heating fluid forced in through the inlet pipe 8.

The next inner pipe 12 has also an upper stuffing box 13 which furnishes a sliding fluid tight connection outside the next inner air pipe 20. The pipe 12 is slidable longitudinally by telescoping within the outer pipe 2. It is spaced well within the outer pipe to provide a wide space 15 for the circulating fluid and is increased in diameter at a point 14 intermediate its ends. Immediately below this enlargement it is provided with a series of outer packing rings 18 held between the coupling 16 and the packing ring 17. Below the coupling, the pipe 12 is imperforate but at the point 14 of enlargement 100 and immediately thereabove it is perforated at 19 sufficiently to allow the inlet of the desired volume of heating fluid.

The air pipe 20, next within the slidable pipe 12, has at its upper end an inlet T 24 110 with the lateral inlet pipe 25 leading to an air compressor, or steam boiler, not

2
shown. The stuffing box 26 at the upper end of the T 24 receives the sulfur exit pipe 27. The pipe 20 is a straight pipe, imperforate throughout its length except at the point 5 22 near the bottom of the well. The lower end of the pipe is threaded into the anchoring coupling 4, as at 21, where it is firmly supported. At a point above the perforations 22 the pipe 20 has an annular inwardly 10 extending flange 23 through which the next inner pipe 27 fits loosely.

The innermost pipe 27, of the system, is the sulfur outlet pipe. It has an upper elbow 30 leading to the sulfur receptacle, 15 not shown. It is provided near its lower end with an outer flange or ring 28, fitting loosely within the pipe 20. This flange will, in its lowest position, seat upon the flange 23 previously described and close the passage 20 between the pipes 20 and 27.

At some point spaced above the closure 23, 28, I perforate the pipe 27 at 29, these perforations being few in number.

The operation of my improved device will 25 now be clear. The heating fluid is forced in under pressure through the inlet 8 and down in the space between the pipes 2 and 12 until its further progress in this space is stopped by the packing 18. It then passes 30 through perforations 19 to the space within the slidable pipe 12. From there it passes around the lower end of the pipe 12 and is projected outwardly through perforations 3 to the sulfur stratum. Sulfur melted by the 35 heating fluid flows down into the lower end of the well through perforations 3 and 22 and is forced by the pressure of the heating fluid upwardly within the sulfur outlet pipe 27.

40 Air or steam is forced in through the inlet 25 and downwardly between the pipes 20 and 27 to the point where its progress is barred by the closure 23, 28. It is then forced through the openings 29 into the 45 sulfur pipe 27 where it bubbles upwardly lifting therewith the rising stream of sulfur.

In sulfur or oil wells it has previously been customary to furnish an inlet for the air through a small central pipe within the 50 sulfur pipe but this method has the disadvantage of impeding the progress of the sulfur upwardly due to the friction of the sulfur on this air pipe. Furthermore the air is thereby projected downwardly against 55 the rising sulfur and furnishes a decided back-pressure on the sulfur. The mixture of water, air and sulfur also liberates a certain amount of sulfuric acid which quickly corrodes the central air pipe and causes it to 60 disintegrate and break off in the well necessitating the temporary suspension of the mining operations. My apparatus avoids these defects. By the use of my improve-

ment there is no back pressure on the liquid, and no impediment to the rising stream of 65 sulfur or oil and no inner pipe to corrode and break.

The purpose of my sliding pipe 12 is to direct the current of heating fluid at any point along the sulfur bed as desired. It 7 is obvious that the fluid must pass around the lower end of this pipe, and from that point, will pass directly outwardly into the sulfur, hence the level at which the lower end of the pipe 12 is raised will determine 75 the point in the sulfur bed which is to be worked.

The raising and lowering of the slidable pipe 12 is accomplished by the usual block and tackle used around well derricks. The 80 tackle is secured around the upper end of the pipe and the pipe raised to any point desired. When it is to be lowered the loosening of the tackle will allow it to slide back by gravity to any level where the 85 sulfur bed is to be worked.

Having thus described my invention, what I claim as new, and desire to protect by Letters Patent is:

1. In a system of pipes for sulfur mining, 90 an inlet pipe for heating fluid, an inner outlet pipe for the fused sulfur and means outside said sulfur outlet pipe and inside said inlet pipe for conveying air into the lower portion of said sulfur outlet pipe. 95

2. In an apparatus for sulfur mining, an outer pipe serving as an inlet for the heating fluid, an inner pipe for the sulfur outlet, and an intermediate air inlet pipe, said sulfur outlet pipe being perforated to allow 100 ingress of the air thereto from the air pipe.

3. In an apparatus for sulfur mining, the combination of an outer perforated pipe, an inner sulfur outlet pipe, an intermediate air inlet pipe, coöperating flanges on said air and sulfur pipes to close the passage between them and perforations in said sulfur pipe for the purpose described. 105

4. In a sulfur mining apparatus, the combination of an outer fixed pipe, a slidable pipe within said fixed pipe, an inner discharge pipe, and an air inlet pipe between said discharge pipe and said slidable pipe. 110

5. In an apparatus for sulfur mining the combination of an outer perforated inlet pipe, an inner sulfur outlet pipe, an air inlet pipe between the two first mentioned pipes, and a closure for the space between the air and sulfur pipes, said sulfur pipe being perforated above said closure and said air pipe being perforated below said closure. 115 120

In testimony whereof, I hereunto affix my signature this the 20th day of May, A. D., 1918.

ROBERT E. CARMICHAEL.
